UNITED STATES PATENT OFFICE.

JOHN H. ANDERSON, OF ST. PAUL, MINNESOTA.

PORTFOLIO.

Application filed August 26, 1922. Serial No. 584,514.

The object of my invention is to provide a portfolio in which letters and papers of various kinds can be kept in indexed order and readily accessible at any time.

5 A further object is to provide a portfolio in which provision is made for conveniently carrying letter-heads and envelopes, pens, pencils, and other articles for use in correspondence.

10 A further object is to provide a portfolio having means for holding catalogs or pamphlets in place and

15 A further and particular object is to provide a portfolio adapted to receive the leaves or sheets and index of an ordinary letter file, such as is in general use for filing purposes.

Other objects of the invention will appear from the following detailed description.

The invention consists in various constructions and combinations all as hereinafter described and pointed out in the claims.

In the accompanying drawings forming part of this specification,

20 Figure 1 is a perspective view of my improved portfolio ready for use.

Figure 2 is a view showing the cover removed and the preferred means for fastening the leaves in the case.

25 Figure 3 is a detail view showing the leaf or division plate fastening means.

Figure 4 is a perspective view showing the portfolio open, and the means for holding the leaves in place therein.

30 Figure 5 is a perspective view of the portfolio closed, ready for carrying from place to place, and

Figure 6 is a side view of the same.

In the drawings, 2 represents one of the side walls of the portfolio, 3, the end walls, 40 and 4, the back or rear wall made preferably of wood to provide a non-yielding construction, or any other suitable material, such as stiff leather or strawboard, or even a light metal may be used if preferred.

45 5, is the cover forming the other side wall hinged to the rear wall 4, and adapted to close one side of the portfolio, and having an extension 6 at its outer end, which when the portfolio is closed, forms the top thereof; 50 this extension being preferably of wood, comparatively thick, and having preferably a curved outer surface 7. When the cover is closed, the edge of this extension will rest upon the upper edge of the wall 2 on the 55 opposite side of the portfolio, and effectually

close the same and prevent the entrance of dust and dirt therein. When this cover is thrown back, the whole interior and contents of the portfolio are exposed.

The rear wall of the case is provided with 60 a T slot 8, extending transversely of its middle portion, and the leaves of the file 9 placed in the case have T-shaped tongues 10 thereon which are adapted to enter the slot 8 and hold the leaves in place until such time as 65 it is desired to remove the file from the case.

A plate 11 is fastened to the rear wall of the case and overhangs the inner edges of the leaves, and to this plate, the outer leaf or cover 9^a of the file is hinged. The plate 70 11 is comparatively stiff and prevents the leaves of the file from becoming accidentally separated from the slot 8, while the portfolio is in use. The file is indexed in the usual way, corresponding to an ordinary letter file, and the user of the portfolio can place his 75 papers therein under the appropriate filing letter and have immediate and convenient access thereto whenever desired. Correspondence of all kinds can be kept in the 80 file, both the letters received, and those answered, and memoranda, bills, contracts, or other documents can also be conveniently kept and easily found when wanted.

I prefer to provide bars 12 fastened to the 85 wall 2, dividing the interior into narrow compartments 13 and 14, on one side of the file; the former being adapted to receive envelopes, and the latter, letter-heads.

A plate 12^a is fitted into the case upon the 90 bars 12 and spaced thereby from the wall 2 to aid in holding the envelopes and letter-heads in place in the compartments 13 and 14. These compartments may, if preferred, be used for the convenient carrying of photographs, pamphlets, or trade catalogs. 95

Partitions 15 are also provided within the 100 casing forming pockets 16 in which stamps, pencils, pens, matches, and various other small articles can be conveniently carried and readily accessible whenever desired.

The cover 9^a can also be used as a bulletin 105 sheet on which price-lists and data of various kinds may be fastened for convenience of reference, and on the inside of the cover 5, I prefer to mount a strap 17 of flexible material under which various articles such as catalogs, pamphlets, etc., may be carried.

On the outer surface of the wall 2, straps 110^a are mounted under which newspapers,

magazines, and the like can be carried. For holding the portfolio in its closed position, I provide a strap 18 secured at one end to the wall 2 and having a key controlled locking means at 19, and preferably a button 20 is provided on the extension or plate 6, and adapted to enter a socket 21 in the strap. This is a measure of safety to prevent the accidental opening of the portfolio in case the locking device 19 should become unfastened.

In various ways the details of construction herein shown and described, may be modified and still be within the scope of my invention.

15 I claim as my invention:

1. A portfolio comprising a casing having a side wall hinged thereon, an extension fixedly secured to said hinged side wall and composed of comparatively thick material 20 having a curved outer surface forming the top of the portfolio, and a strap having one portion secured to the case and adapted to swing over and about the extension, said extension and strap having means enabling 25 them to be detachably connected.

2. The combination with a case, of an index file fitting therein, the leaves of said file having means for interlocking with a wall of said case, a plate secured to said wall and 30 overhanging said interlocking means, the outer cover of the file being hinged to said plate.

3. A portfolio comprising a case, having a side wall hinged thereon, an extension secured to said side wall and having a curved outer surface forming the top of the portfolio, a strap secured to the wall of said case on one side and having means for interlocking with the wall of said case on the 40 opposite side, said strap having a socket in-

termediate its ends for receiving a button in the surface of said extension.

4. A portfolio comprising a case, an index file fitting therein, one of the side walls and an end wall of said case being adapted to 45 swing open to expose said file, and bars spacing said file from the other side wall of said case to provide compartments adapted to receive envelopes and letter-heads.

5. The combination with a case, of an index file fitting therein, the leaves of said file, and a wall of said case having means for interlocking, a cover for said leaves secured to said case, and overhanging said interlocking means and preventing the accidental separation of the file leaves from the wall of the case.

6. A portfolio comprising a case having a hinged side wall adapted to be opened to expose the interior of the case, an index file 60 arranged within said case, and having means for connecting it to the rear wall thereof, said case having pockets formed therein at each end of said index file, adapted to receive pencils, pens and the like.

7. A portfolio comprising a casing having a hinged side wall forming a cover, an index file fitting within said case and having means for connecting it to a wall thereof, bars arranged within said case beneath said index 70 file and cooperating with the latter and with a side wall of said case to form pockets for stationery and the like, and said case having pockets formed thereon on each side of said index leaves adapted to receive pencils, 75 pens and the like.

In witness whereof, I have hereunto set my hand this 23d day of August, 1922.

JOHN H. ANDERSON.
